UNITED STATES PATENT OFFICE.

JAMES O. KAFADER AND FRANK KERR, OF FORT BIDWELL, CALIFORNIA.

LOCK AND LATCH.

1,169,649.

Specification of Letters Patent.

Patented Jan. 25, 1916.

Application filed May 26, 1914. Serial No. 841,030.

To all whom it may concern:

Be it known that we, JAMES O. KAFADER and FRANK KERR, citizens of the United States, and residents of Fort Bidwell, in the county of Modoc and State of California, have invented certain new and useful Improvements in Locks and Latches, of which the following is a specification.

This invention relates to means for preventing unlawful or unauthorized entry into buildings, or rooms or closets therein, trunks, chests, etc.

A further intent is to engage a key or tool used in such unauthorized entry and hold the same against removal by locking the lock bolt against movement in either direction.

A further object is to provide means, within a building to make the device inoperative.

A further object is to provide means, also within the building, for actuating the bolt, from locked position of the key therein, into retracted position; and further objects are to provide such devices which are simple in construction, readily installed, highly efficient, and comparatively inexpensive.

The invention is fully set forth in the following specification, of which the accompanying drawings form a part, in which the same reference characters are used to designate the same parts in each of the views, and in which:—

Figure 1 is an inner elevation of a door provided with our invention; Fig. 2 is an enlarged, fragmentary view of the door with a plate which we employ removed; Fig. 3 is an enlarged section on the line 3—3 of Fig. 1, with the parts in key engaged position and sounding of the alarm; Fig. 4 is a similar view but showing the parts in "ready" position, the door being locked; and Fig. 5 is a similar view of a modification, with the parts in the positions shown in Fig. 3.

In the drawings forming a part of this application we have shown a door a and frame a^2 thereof, said door having the usual or any desired lock a^3 provided with the sliding bolt a^4 operable by means of a key a^5 , all these parts being of conventional form with the exception that we provide a vertical slot a^6 on the inner side of the bolt a^4 , and which forms an important part of this invention.

Mounted in the frame a^2 , adjacent the door, is a casing b , preferably of porcelain

or other non-conductive material, having a metal covering plate b^2 secured to the inner side of the frame, and said casing contains a lever b^3 having arms b^4 and b^5 , arranged 60 at a right-angle, and pivoted at b^6 , said arm b^5 extending through the frame and carrying a pin b^7 which projects into the bolt recess behind the striking-plate of the door frame, and in the path of the bolt, said arm 65 also carrying an oppositely directed pin b^8 which extends to a recess b^9 in the casing b .

Within the casing, beneath the face plate b^2 , and adapted to be locked thereto by means of a thumb-nut c , is a slide c^2 adapted 70 to bear against the arm b^4 of the lever b^3 to maintain the arm b^5 in a position substantially parallel to the face of the door frame. As clearly shown in Fig. 4, we may, if desired, provide two electrical contacts d and 75 d^2 , the former of which supports a conductive spring plate d^3 , and said contacts are in electrical connection with wires d^4 and d^5 of an electrical circuit adapted to be closed through the plate d^3 and through an electric 80 bell d^6 , Fig. 1, or, if desired, through an electric light as well, not shown, and which might be arranged in any part of a building or many lights might be so connected to illuminate the entire building; by reference 85 to Fig. 4, it will be seen that the pin b^8 holds the plate d^3 against the elasticity thereof but, if said pin be withdrawn, said plate closes the circuit through the two contacts, as shown in Fig. 3, thereby energizing 90 the alarms; this electric system, however, forms no part of the present invention but may be made the subject matter of a subsequent application for patent.

The parts are normally in the positions 95 shown in Fig. 4, with the pin b^7 partially withdrawn and out of the path of the bolt a^4 , and held so by means of the slide c^2 , and the door may be readily locked and unlocked but, if the slide c^2 be actuated to release the lever b^3 , as when the occupants of a dwelling retire for the night, our device becomes "ready" and operative in the event of unauthorized tampering with the lock, this being true even of the householder 100 who may be out of the house. When the key a^5 is inserted into the lock and turned to retract the bolt a^4 , said bolt is retracted, for a short distance, until the pin b^7 enters the slot a^6 , being forced thereinto by means 105 of the spring plate d^3 , and said bolt is held against movement in either direction. The

bolts of door locks are usually provided with a notch, each, sometimes V-shaped, into which the leaf of the key enters, said leaf abutting against one edge of said notch 5 to move the bolt in one direction, and against the other edge of said notch to move the bolt in the opposite direction, and the leaf of the key is engaged in said notch in all the positions of the bolt other than its 10 two extreme positions, this being of old and well known construction. It will thus be seen that, when the bolt is imprisoned by means of the pin b^7 , and the key leaf is imprisoned in the notch of the bolt, said key 15 cannot be rotated in either direction, nor removed from the lock. When the lever b^3 is thus moved on its pivot by the plate d^3 , said plate closes the electrical circuit described by means of the contact d^2 and the 20 house occupants are notified that an attempt is being made to open the door and, if it be a member of the household, the slide c^2 may be actuated to return the parts to normal positions, with the bolt free, but 25 the key is useless at the angle at which it was imprisoned, in most locks of this type, and to overcome this a turn-button e is provided, within the building, having a shaft secured thereto extending within the 30 door frame where it carries an arm e^2 in turn pivoted to a slide e^3 adapted to impinge on the end of the bolt, and it will be seen that by turning the said button the bolt may be forced into retracted position 35 and the door opened from within or from the outside.

The form thus far described has the disadvantage of preventing the locking of the door, with the parts in readiness for operating in the manner set forth, by means of a key, this being overcome by beveling the face of the pin b^7 , as clearly shown in Fig. 5, whereby the bolt, in its outward movement, may force the said pin out of its path

but, upon attempting to retract the bolt to 45 open the door, said pin enters the slot of the bolt as already described.

The invention therefore consists, primarily, of means for preventing the unlocking of a door and for imprisoning the key; 50 secondly, of means for making the device inoperative; and thirdly, of means for forcing the bolt into retracted position; with a reservation to ourselves of all forms of construction making these results possible, 55 within the scope of the following claims, what we claim as new, and desire to secure by Letters Patent, is:—

1. The combination with a door, door frame, and lock having a sliding bolt; of 60 means connected with said door frame for engaging said bolt to arrest the same intermediate its full movement, means for releasing said engaging means, a slide adapted to bear against the outer end of said 65 bolt, and means for actuating said slide to retract said bolt when released from said engaging means.

2. The combination with a door, door frame, and lock having a sliding bolt; of 70 means connected with said door frame for engaging said bolt to arrest the same intermediate its full movement, means for releasing said engaging means, means for making said engaging means inoperative, 75 a slide adapted to bear against the outer end of said bolt, and means for actuating said slide to retract said bolt when released from said engaging means.

In testimony that we claim the foregoing 80 as our invention we have signed our names in presence of the subscribing witnesses.

JAMES O. KAFADER.
FRANK KERR.
